(57) **CLAIM**

The ornamental design for a sippy cup with a flip lid and straw, as shown and described.

DESCRIPTION

FIG. 1 is a front left perspective view of a sippy cup with a flip lid and straw in a closed position showing my new design; the front right perspective view being a mirror image thereof;

FIG. 2 is a front left perspective view of FIG. 1 with a flip lid and straw in an open position; the front right perspective view being a mirror image thereof;

FIG. 3 is a rear left perspective view of FIG. 1; the rear right perspective view being a mirror image thereof;

FIG. 4 is a top plan view of FIG. 1;

FIG. 5 is a front view of FIG. 1;

FIG. 6 is a right side view of FIG. 1; the left side view being a mirror image thereof;

FIG. 7 is a rear, right side bottom perspective view of FIG. 1;

FIG. 8 is a rear bottom perspective view of FIG. 1;

FIG. 9 is a rear, left side bottom perspective view of FIG. 1; FIG. 10 is another rear, right side bottom perspective view of FIG. 1; the rear, left side bottom perspective view being a mirror image thereof;

FIG. 11 is a bottom perspective view of FIG. 1; and,

FIG. 12 is a top front perspective view of FIG. 1 with an unclaimed handle.

The broken lines depicted in FIG. 12 show the environment in which the design is associated and form no part of the claimed design.

1 Claim, 12 Drawing Sheets
